UNITED STATES PATENT OFFICE.

LEON VERBEECK AND EDUARD DE RAET, OF BRUSSELS, BELGIUM.

TUBE-EXPANDER.

SPECIFICATION forming part of Letters Patent No. 372,995, dated November 8, 1887.

Application filed July 6, 1886. Serial No. 207,228. (No model.) Patented in Belgium May 4, 1886, No. 53,863.

To all whom it may concern:

Be it known that we, LEON VERBEECK and EDUARD DE RAET, residents of Brussels, in the Kingdom of Belgium, have invented a new and useful Improvement in Tube-Expanders, (for which we have obtained a patent in Belgium, numbered 53,863, and dated May 4, 1886,) of which the following is a specification.

The object of our invention is to provide a tube-expander which is simple and durable and which can be operated with rapidity, and has reference particularly to a tube-expander to be used in causing the thickness of the tube or pipe to enter a circumferential groove or mortise in the annular surface of the seat in which the pipe is to be fitted; and our invention consists in features of novelty hereinafter fully described, and then pointed out in the claims.

In order that our invention may be fully understood, we will proceed to describe the same with reference to the accompanying drawings, in which—

Figure I is a view of one of the thimbles of our tool, showing the manner in which it acts upon a pipe when jointing it to a flange or other seat. Fig. II is a plan of the tool employed for carrying out the process. Fig. III is an elevation of one of the branches of the latter, carrying its thimble or rotary die.

By preference, the tool consists of three branches having a common center and forming equal angles with one another. Starting from the center, for a certain portion of their length the branches are of square or rectangular section and terminate in handles M, forming powerful levers when the tool is in position for working. On the rectangular portions of the branches thimble-carriers P are mounted in such a manner that they can be adjusted longitudinally thereof. In the present example, two of these latter are adjustable on their corresponding branch, which has a number of teeth, with which the pawl C engages; but they may all be adjusted equally with the third, which is inserted in a recess or slot made in its branch and traversed by a nut-screw, V, which is a prolongation of the handle M, by whose aid it may be turned without being displaced longitudinally, so as thus to actuate the thimble-carrier according to requirements. In order to displace the pawl

thimble-carriers, it will be readily seen that it suffices to raise the pawls and to make the carriers slide on their toothed branch to the 55 desired place.

It is evident that other mechanical combinations may also be employed for adjusting the thimble-carriers, and that consequently we do not restrict ourselves to the arrangement 60 described. The steel thimble X has its longitudinal section, as shown in Fig. 1, with the projecting rib or collar n and the conical base e. It is mounted on the thimble-carrier P in such a manner as to turn loosely on a pivot of 65 the latter, to which it is held by a screw with nicked head. If the tool thus made is so placed that the ribs or collars n of the thimbles X are pressed against the inside of the pipe, the end which is introduced into its 70 flange or other seat, provided with the groove or annular mortise mentioned above, and the thimbles X be turned by means of the handles M, the annular thickness of the tube enters the groove of the seating, into which it is forced 75 or set by the ribs or collars n, gradually drawn by the screw V in such a manner that the two parts become, as it were, one, and present a thickness that stands all tests. At the same time the end of the tube is bent back or “up-set” upon the seat under the pressure of the 80 conical portion e of the thimble—an operation which still further increases the tightness of the joint.

Instead of a single mortise, two or more may 85 be made in the flange or other seat of the pipe, to which correspond two or more ribs or collars on the thimble. Perfect tightness may even be obtained by simply threading the interior of the pipe-seat and rolling the surface 90 of the tube against the threaded seat by means of a plain thimble—that is to say, without any rib or collar—an arrangement which also produces a thoroughly tight joint. In a word, the thimble may be provided with ribs or collars of any section and number corresponding 95 with the recesses or mortises made in the seating. A tool may also be used with only one branch and one thimble by giving it a suitable fulcrum, or even a tool with two branches; 100 but experience shows that three, five, or any uneven number of branches, according to the diameter of the pipe, are far preferable.

It is evident that the tool may be made of

any suitable material and of any size, and that the process may be applied to all forged or drawn tubes of any malleable metal. Moreover, this process is applicable to all connections or insertions of pipes employed in manufacture, one of the most important applications being, for instance, the fitting of tubes in steam-boilers, &c.

Having thus described our invention, the following is what we claim as new therein and desire to secure by Letters Patent:

1. In a tube-expander, the combination, with a number of radiating branches, each of which is provided with a handle, of adjustable slides or carriers on said branches provided with revolute thimbles, substantially as and for the purpose set forth.

2. In a tube-expander, the combination, with a number of radiating branches, one of which is slotted, of adjustable slides or thimble-carriers on said branches, and a handle having a screw-threaded prolongation adapted to work through the end of the slotted branch and engage the thimble-carrier on said branch, substantially as and for the purpose set forth.

3. In combination with the flanging or up-setting devices of a tube-expander, a series of radiating handles for operating them, substantially as set forth.

4. In combination with the flanging or up-setting devices of a tube-expander, an adjusting-handle for one of said flanging devices, constituting, in connection with other handles, the means for operating the expander, substantially as and for the purpose set forth.

5. In a tube-expander, the combination, with a number of radiating branches, each of which is provided with a handle, of adjustable slides or carriers provided with pivot-pins, thimbles adapted to revolve on said pins, and screws for retaining said thimbles on the pivot-pins, substantially as set forth.

LEON VERBEECK.

ED. DE RAET.
